MANIFOLDING DEVICE

Carl W. Brenn, Montclair, N. J., assignor to Autographic Register Company, Hoboken, N. J., a corporation of New Jersey

Application May 6, 1938, Serial No. 206,361

19 Claims. (Cl. 282—3)

This invention relates to manifolding devices, and, more particularly, to a package comprising a supply of continuous-form stationery, and a container for the same including a writing surface on which the forms are placed and interleaved with transfer material. In my patent, No. 1,999,535, granted April 30, 1935, I have disclosed such a package of manifolding stationery, and the present invention relates to improvements on this package.

One of the features of this invention is the provision of a completely enclosed package, with provision for the easy and definite removal of a portion of the package, which will thereafter expose to writing operations a set of manifolding forms interleaved with transfer material.

Another feature of this invention is the provision of means whereby the under or duplicate copies may not be marked during shipment of the package.

Another feature of this invention is an improved form of outside container which may be assembled and stored in knockdown form, and which may be readily folded into shape to receive an inner part thereof, and which may be conveniently strengthened by corner pieces.

Still another feature of the invention is the provision of an improved thin sheet metal plate serving as a platen on which the writing operations are performed, and having at one end improved means for mounting and supporting the transfer material, which is in sheet form, between the plies of the printed stationery, which is preferably of the fanfold type.

Other features and advantages will hereinafter appear.

In the drawings:

Figure 1 is a plan view, partly in section, of the package.

Fig. 2 is a longitudinal sectional view of the package shown in Fig. 1.

Fig. 3 is a diagrammatical view showing the relation of the forms and transfer strips on the platen.

Fig. 4 is a detail sectional view of the carbon sheet anchoring means.

Fig. 5 is a perspective view of the inner casing.

Fig. 6 is a plan view of the blank forming the inner casing.

Fig. 7 is a perspective view of the front section of the outer casing, showing the overlapped front wall.

Fig. 8 is a bottom perspective view of the writing platen.

Fig. 9 shows the completed package ready for shipment.

Fig. 10 shows the blank for forming the outer part of the casing.

Fig. 11 shows a perspective of the package, with the removable section partly removed.

Fig. 12 is a perspective view of the package, showing the protecting strips in place.

Fig. 13 is a diagrammatical view of the manifolding material on the platen, with the protecting strips in place.

Fig. 14 is a perspective view of the package as ready for use, showing the finger-grip opening and the release for the pins.

Fig. 15 is a fragmentary view showing a guide roller in section for assisting in the feeding of the strips from the storage compartment.

Fig. 16 is a fragmentary sectional view along line 16—16 of Fig. 15.

The manifolding package of the present invention includes a casing having stored therein a pile of continuous writing strips, and provided with a metal writing plate over which the strips are passed and upon which the writing operation takes place. This package is intended to be used without removing the pile from the package—the container forming a portable register.

The casing is made of a paper like material so that after the supply of continuous strips has been exhausted, it can be discarded. In the preferred form of the invention, the casing is sealed so that the supply of forms therein cannot be renewed without rendering the casing useless as a register.

As shown in the drawings, the casing is made in two parts, one disposed within the other. The inner part or casing 20 carries the supply of stationery material and is formed from a single blank of corrugated board, as shown in Fig. 6. The blank is cut along the solid lines and is folded along the dotted lines. The corners 21 of the blank are folded so as to extend perpendicularly to the plane of the paper, and the end walls 22 and 23 are then folded along their bottom line, thus disposing the corners along the sides of the casing. The side walls 24 are then folded up and secured to the corners, thus forming a box having a bottom and end walls of single-ply thickness and side walls of double-ply thickness for substantially the major portion of their length. The side walls will be strengthened against compression under writing pressure, because, in folding up the side walls and corners, the corrugations in the two plies will be at right angles to one another. The end wall 22 is pro-

vided with an opening 25, for a purpose to be later explained.

The stationery carried by the casing can be of different form lengths. In order that the single size of inner casing can properly hold the forms of various lengths against shifting in the casing during shipment, a partition or transverse wall 26 is provided to extend across the inner member and form a supply compartment 10 which will snugly fit the desired form. The partition can be disposed in the casing in proper position to form a compartment which will accommodate forms of the desired lengths. It is locked in place by having portions 26a which extend along the side walls and are secured thereto. The locating of the partition is done before the plies of the side walls are secured together so that staples 27, when driven through the two plies of the side wall, will also pierce the portions 20 26a of the transverse wall and lock them all together.

As is shown in Fig. 2, a pile 30 of zigzag folded stationery is disposed in the supply compartment so as to substantially fill the same. The 25 stationery is in the form of a continuous strip 31 having forms 32 printed thereon in succession. The forms are separated by tear lines 33, preferably lines of perforation, and are each provided with holes 34 to be used to locate the sheet 30 in writing position. The stationery illustrated is of the fanfold type in which alternate side margins of the superposed strips are connected, see Fig. 3. If desired, however, piles of separate, superposed continuous strips can be used.

35 Inasmuch as the manifolding stationery is to be used without removing the pile from the casing, a writing plate or platen 36 is disposed over the inner casing to receive the continuous strips from the pile and support them for a writing or manifolding operation. The writing platen is secured to the inner member so as to be supported by the side walls and to be held thereon.

The writing plate is held against lateral movement on the inner casing by depending flanges 45 or ears 37 which are formed on the sides thereof adjacent one end and received in pockets 38 formed between the two secured-together plies of the side wall and held against longitudinal movement by a flange 39 engaging the outer surface of the end wall of the casing.

50 When the platen rests on the tops of the side walls of the inner casing, pressure applied thereon during writing operations will tend to cause the walls to move laterally and spread or collapse. With the dependent ears disposed between the plies of the side walls, however, the walls are securely braced and held against lateral movement either inwardly or outwardly of the casing.

60 As shown in Figs. 1 and 2, the writing plate has a free end 40 having a curl 49a thereon which extends partially over the supply compartment and into receiving relation with the strips therein. The free end of the platen is supported by having 65 its edges resting on the edges of the inner casing and the portions 26a of the partition which provide an adequate supporting surface.

The platen is further supported intermediate its ends, where the writing pressure is applied, 70 by the partition 26 which is extended into engagement with the undersurface of the platen, as shown in Fig. 2. The partition 26, in the preferred form of the invention, is made from corrugated board and is positioned in the casing 75 with the corrugations extending perpendicular to

the plane of the platen, as shown in Figs. 2 and 5, so that a maximum supporting strength is obtained.

In order that the written impressions will be made on all of the record forms disposed on the platen, a plurality of sheets of carbon paper or transfer material 41 are carried by the platen to overlie the same and be interleaved with the record strips to form a manifolding pile as shown in Fig. 3.

10 The carbon sheets have a clip or strip of thin metal 42 clamped to the edge of the sheet first engaged by the record strips. The metal clip is extended beyond the sides of the carbon sheets as shown at 42a, one side if fanfold material is used, or both sides if separate superposed strips are used, and is utilized to secure the sheets on the writing plate.

15 The carbon sheets must be anchored to the platen so that they will not move longitudinally with the record strips when the latter are fed over the platen and also against becoming loose and free when the package is placed in various positions during shipment and during the time when it is carried from place to place in use.

20 The novel anchoring means of the present invention, for locking the carbon sheets in place on the platen, comprises a pin 45 disposed on each margin of the plate beyond the edges of the writing strips and adjacent the free end 30 thereof and a bendable metal tongue 46 preferably having a portion 46a secured to the undersurface of the writing plate so as not to interfere with the passage of the paper over the plate, with the end thereof extending through an opening in the plate in juxtaposition with each pin. The extension 42a of the clip 42 secured to the carbon sheets is provided with a hole 47 for engaging the pin and with a rectangular aperture 48 exactly receiving the bendable tongue. The pin 45 has an extension 45a projecting from the undersurface of the platen. The extension is pointed, as shown in Figs. 3 and 4, so that it will readily penetrate into the material of the side walls as shown in Fig. 15 upon which the platen rests and aids in holding the platen in position on the inner member.

25 As is shown in Fig. 1, the pin and tongue are placed on a diagonal with respect to the longitudinal axis of the casing, and also to the longitudinal axis of the clip which is perpendicular to the longitudinal axis of the casing. This will effectively hold the clip and carbon sheet against longitudinal movement with the record strips.

30 After the clip has been positioned with the pin 55 and tongue in the openings therein, the tongue is bent into overlapped relation with the clip, as shown in Fig. 4, and the latter is effectively locked against separation from the platen in all positions of the casing. The tongue, however, is 60 bent so that it will not clamp the carbon sheet tightly to the platen but will permit it to rest freely on the writing strip.

35 The strips are properly located on the platen by a pair of intercepting pins 50 which are positioned at the forward end of the platen to engage the holes 34 in the strips and stop the feeding of the strips when they reach the proper writing position on the platen. The pins can be released when it is desired to withdraw the written form.

40 The pins are carried by a spring plate 55 secured to the undersurface of the platen, as shown in Fig. 2, which plate normally urges the pins through apertures in the plate and into a posi- 75

tion wherein they will engage the holes 34 in the paper. The plate is extended, as shown in Figs. 1, 2 and 8, to provide a release lever 56 to be engaged to move the plate 55 and the pins 5 against the action of the spring into release position. The partition is so disposed in the casing that the release lever will always be free to be moved into release position.

The releasing lever is disposed behind the front depending flange 39 of the platen which is provided with an aperture 57 in alignment with opening 25 in the end wall of the casing.

As shown in Fig. 8, the pins can be released by inserting a finger through the opening in the end of the casing and pressing the lever 56 downwardly. If desired, the pins can be automatically released by the fingers when they are moved into the opening and in gripping relation with the ends of the strips so as to withdraw the written set of forms and place a fresh set of forms on the platen.

A hold-down bar 51 is mounted on the platen to overlie the strips and is provided with holes 52 to receive the pins 50. With the pins extending through the holes 34 and into the holes in the bar, the strips are held against accidental displacement from the intercepting pins during shipping and handling of the casing.

The package is shipped with a set of forms in manifolding position on the platen. In order to prevent pressure on the sheets, occurring during shipment, from causing the transfer sheets to mar the under or duplicate copies, means have been provided for protecting them. While this may be of any type, the herein preferred form comprises placing dummy or protecting sheets 75 and 76, as shown in Fig. 13, so that they lie between the transfer sheet and the record sheet, and any marks transferred from the transfer sheet by pressure upon the top of the package will be received by the dummy sheets. The protecting sheets are provided with holes through which the pins 50 extend and are thus locked in place. The sheets are provided with finger tabs 77 which extend into the finger-grip opening, as shown in Fig. 12, and can be readily gripped and slipped from their position within the manifolding pack when the pins are released and it is desired to use the pile for manifolding purposes.

The protecting sheets 75 and 76 are secured together by a staple 78, as shown in Fig. 12, so that they will be removed from the pile upon pulling tabs 77.

The package is completed by providing an outer casing 59 which completely encloses and protects the inner casing 20 carrying the writing plate or platen 36 and the supply of manifolding stationery, as shown in Figs. 1, 2, 9 and 11.

The outer casing is made of cardboard or chipboard and is folded up from the flat blank. It can be readily stored in flat condition until the packages are made up, and will take up very little storage space. The blank, which is shown in Fig. 10, forms top, bottom, end and side walls, by being cut along the heavy lines and folded along the dotted lines.

In folding up the outer casing from the blank, a pair of sections 60 are folded about the dotted lines so as to be perpendicular to a pair of side walls 61. The side walls 61 are then folded perpendicular to a bottom 67, and an end wall 62 is then folded along the bottom fold line to be perpendicular to the bottom and the sections 60 secured to the inner surface thereof. A pair of side walls 63, secured to a top section 68, are

then folded along the fold lines and are inserted so that they engage the inner surface of the side walls 61 and are secured thereto.

This construction provides a rigid housing having single-ply top and bottom walls and the side walls with the intervening end wall of double thickness.

The top wall 68 and end wall 62, as shown in Figs. 9 and 10, have a pair of connected portions 69 and 70 which are weakened by being cut as indicated by the heavy lines and held in place by frangible portions 72 at spaced intervals.

The sections 60 have the corners thereof cut as at 71, so that when they are in folded relation they will not overlap the portion 70, which is to be removed from the end wall 62. This is clearly shown in Fig. 7.

After the walls of the outer casing have been secured together, the inner casing is prepared by interleaving the carbon sheets and protecting sheets with the first set of forms on the continuous record strips and disposing them over the platen in proper manifolding relation. The inner section is then slipped into the outer casing through the open end thereof with the end having the platen mounted thereon being inserted first.

The casing is closed by folding a pair of flaps 64 along the fold lines and an end 65 folded along its fold line disposing the flaps between the side walls 61 and 63. An end flap 66 is inserted under the top wall and all are sealed in place. The package is now ready for shipment.

With the inner casing completely enclosed on all sides and top and bottom by the outer casing, the platen and manifolding material will be fully protected.

When it is desired to use the casing, the tab 70, which is disposed over the opening 25 in the end of the inner member, is released by breaking the frangible connections 72. This can be readily done by pushing against the unsupported tab. The tab is pulled forward, as indicated by the arrows in Fig. 11, thus breaking the remaining connections 72 and releasing the section 69 for removal from the top wall. This forms a writing opening in the top disposed over the platen and exposing the forms for manifolding purposes.

When the tab 70 is removed from the end wall 62, a finger-grip opening is formed (see Figs. 2 and 14) in alignment with the opening 25 and 57 in the end wall of the inner casing and flange in the platen whereby the ends of the strips can be readily gripped and withdrawn.

As will be noted in Figs. 9 and 11, the side edges of the opening extend over the writing strips for a major portion of their length and are curved outwardly toward the edges of the casing at the end thereof to release the strip from control of the top section, so that it can be readily severed from the continuous strip.

If desired, the casing can be provided with strengthening ribs, such as box fasteners 73 secured along the side corners, as shown in Figs. 9 and 11, to reinforce the top against accidental removal from the casing.

In some instances, it may be desirable to provide a means for guiding the strips as they emerge from the storage compartment. While guides of various types may be used, a roller 89 has been illustrated in the form of the invention shown in Figs. 15 and 16, over which the strips pass in their movement toward the platen. The roller is disposed adjacent the end of the platen and extends transversely of the storage compartment.

While the roller can be mounted in the compartment in any desired manner, in the preferred form of the invention it is provided with a pair of conical trunnions 81, one at each end, which are adapted to be forced into the material of the side walls as illustrated in Fig. 16 to rotatably support the roller in the casing as the strips are fed from the storage compartment to the platen.

10. Variations and modifications may be made within the scope of this invention and portions of the improvements may be used without others.

I claim:

1. A manifolding device comprising a casing including inner and outer parts having their walls mainly of fibrous material; and a rigid writing plate interposed between the two parts and disposed below the top wall of the outer part, the outer part completely enclosing the inner part and having a portion of the top wall disposed above the writing plate removable to form a writing opening therein.

2. A manifolding device comprising a casing including inner and outer parts having their walls mainly of fibrous material; and a rigid writing plate interposed between the two parts and below the top wall of the outer part, the writing plate supporting printed forms carried by the inner part in manifolding relation, the outer part completely enclosing the inner part, the plate and manifolding material to protect them during shipment and having a part thereof removable to form a writing opening.

3. A manifolding device comprising a casing including inner and outer parts having walls mainly of fibrous material; a rigid writing plate interposed between the two parts and disposed below the top wall of the outer part, the outer part completely enclosing the inner part and having a portion of the top wall disposed above the writing plate removable to form a writing opening; and bracing ribs running along the side corners of the outer section and overlying the top for substantially the width of the margin of the writing opening.

4. A manifolding device comprising a casing including inner and outer parts having their walls mainly of fibrous material; and a rigid writing plate interposed between the two parts and disposed below the top wall of the outer part, the outer part being folded up from a single flat blank so as to enclose all sides of the inner part and having that part disposed over the writing plate removable to form a writing opening.

5. A manifolding device comprising a casing including inner and outer parts having their walls mainly of fibrous material; and a rigid writing plate interposed between the two parts and disposed below the top wall of the outer part, the outer part being folded up from a single flat blank so as to form top, bottom, side and end walls with the side walls and an end wall of two-ply thickness with the top wall having a portion thereof weakened for ready removal to form a writing opening therein.

6. A manifolding device comprising a casing including inner and outer parts having their walls mainly of fibrous material; and a rigid writing plate interposed between the two parts and disposed below the top wall of the outer part, the outer part having a portion of the top wall above the plate weakened so as to be readily removable to form a writing opening.

7. A manifolding assemblage comprising a casing including inner and outer parts having their

walls mainly of fibrous material; a rigid writing plate interposed between the two parts and disposed below the top wall of the outer part, the outer part being provided with a writing opening; a plurality of carbon sheets disposed over the writing plate; a holding bar for each carbon sheet and means for anchoring alternate carbon holding bars at one end only to opposite sides of the plate whereby the carbon sheets can be interleaved with piles of record sheets of the fanfold type, said means including a tongue bendable over the anchored end portion of each holding bar to lock the same to the plate.

8. In a manifolding assemblage, a writing platen over which writing strips are carried; a plurality of carbon sheets disposed on the platen to be interleaved with the writing strips and having a clip attached to one end to extend beyond at least one lateral edge thereof; and means for locking the clip to the platen comprising a pin and a bendable tongue in spaced relation on the platen, the clip being provided with openings in the extension thereof for receiving the pin and tongue after which the tongue is bent to overlap the clip and lock the carbon sheet to the platen.

9. A manifolding assemblage comprising a casing containing continuous strips; a writing platen; a plurality of carbon sheets disposed on the platen to be interleaved with the writing strips and having a clip attached to one end to extend beyond at least one lateral edge thereof; and means for locking the clip to the platen comprising a pin and a bendable tongue in spaced relation on the platen, the clip being provided with an opening to receive the pin and a rectangular opening to receive the bendable tongue, the openings being in diagonal relation to the longitudinal axis of the clip whereby the clip and attached carbon sheet are locked against movement and removal thereof when the tongue is extended through the opening and bent to overlap the clip.

10. A manifolding device comprising a casing including inner and outer parts having their walls mainly of fibrous material, the side walls of the inner part being formed of a plurality of plies secured together; a metal writing plate interposed between the two parts to extend beneath the top wall of the outer part which is provided with a writing opening; and means extending between the plies of the side walls of the inner member for holding the plate in place.

11. A manifolding device comprising a casing including inner and outer parts having their walls mainly of fibrous material, the side walls of the inner part being formed of a plurality of plies secured together; and a metal writing plate interposed between the two parts to extend beneath the top wall of the outer part which is provided with a writing opening, the plate resting on the side walls of the inner part and having dependent flanges disposed between the plies of the side walls to brace the side walls against lateral movement.

12. A manifolding device comprising a casing including inner and outer parts having their walls mainly of fibrous material; a metal writing plate interposed between the two parts to extend beneath the top wall of the outer part which is provided with a writing opening; and means extending transversely of the inner part and engaging the undersurface of the plate to support it intermediate the ends thereof.

13. A manifolding device comprising a casing

including inner and outer parts having their walls mainly of fibrous material; a metal writing plate interposed between the two parts to extend beneath the top wall of the outer part which is provided with a writing opening; and a partition of fibrous material secured in the inner part and forming a storage compartment therein to carry the manifolding material, the partition engaging the undersurface of the plate intermediate its ends whereby it is supported against writing pressure.

14. In a manifolding assemblage, an inner casing having side and end walls and a transverse wall intermediate the ends thereof to form a supply compartment; a pile of zigzag folded continuous strips disposed in the supply compartment; a writing platen secured to rest on the top edges of the walls of the inner casing and over which the continuous strips are fed; and an outer casing having top, bottom, side and end walls surrounding the sides of the inner casing, a portion of the top and adjacent end wall of the outer casing being removable to form a writing opening over the platen and to afford access to the ends 25 of the strips so that they can be grasped and advanced to bring fresh portions of the strips to writing position.

15. As an article of manufacture, a manifolding assemblage comprising a casing including an inner part and an outer part, the inner part having a transverse partition to form a supply compartment; a pile of zigzag folded continuous strips carried by and substantially filling the supply compartment; a platen over which the strips are led resting on the top of the side walls of the inner part and having depending portions bracingly engaging the side walls of the inner part to hold them against lateral movement, a plurality of carbon sheets disposed over the platen in interleaved relation with the continuous strips; and means including a bendable element for locking the carbon sheets to the platen, the outer part of the casing enclosing all sides of the inner part to protect the inner part, platen and manifolding material during shipment and having a portion of the top wall thereof held in place by a frangible connection whereby it can be readily removed to form a writing opening.

16. As an article of manufacture, a manifolding assemblage comprising a casing including an inner and outer part, the inner part having a transverse partition having portions extending along and secured to the side walls thereof and forming a compartment adapted to receive a pile of zigzag folded continuous strips; and a platen, over which the strips are fed, having one end engaging the end wall of the inner part to be held in place thereby and extending so as to partially cover the compartment, the sides adjacent the free end of the platen resting on the portions of the transverse partition secured to the side walls with the transverse partition engaging and supporting the platen intermediate its

ends to thereby receive the writing pressure when the strips on the platen are used, the platen being adapted to support the carbon sheets in interleaved relation with the continuous strips, the outer part of the casing enclosing all sides of the inner part and having a writing opening in the top wall thereof.

17. In a manifolding assemblage, an inner casing forming a container for a pile of zigzag folded continuous writing strips; an end wall of the inner casing having an opening formed therein; a platen for supporting the writing strips in manifolding relation mounted on the top of the side walls of the inner casing and having a dependent flange provided with an aperture extending over the opening in the end wall of the casing with the aperture in alignment with the opening; intercepting pins carried by the platen and normally urged to engage holes in the writing strips to properly position them on the platen; means disposed beneath the platen and operable through the opening in the front of the casing for moving the pins to release position; and an outer casing enclosing the inner casing and having a portion of the top wall and adjacent end wall readily removable to form a writing opening over the platen and an opening in the end wall in alignment with the aperture in the flange of the platen and the opening in the end wall of the inner casing.

18. A manifolding device comprising a casing, including inner and outer parts having their walls mainly of fibrous material; a rigid writing plate interposing the two parts and below the top wall of the outer part, the writing plate supporting the printed forms carried by the inner part in manifolding relation with transfer material, the outer part completely enclosing the inner part, plate and manifolding material to protect them during shipment and having a part removable to form a writing opening when in use; and means interposed in the pile for protecting the under copies from being marked during shipment of the package.

19. In a manifolding assemblage, an inner casing, adapted to carry a pile of zigzag folded continuous strips; a writing platen carried by the inner casing and adapted to support transfer material interleaved with the strips in writing position; an outer casing completely enclosing the inner casing, writing platen and manifolding material during shipment and having a portion of the top and end wall removable to form a writing opening and a finger-grip opening; and a plurality of protecting sheets disposed between the transfer material and the under record sheets during shipment to protect the latter against being marred, the protecting sheets being provided with projecting portions which extend into the finger-grip opening whereby they can be readily removed from the pile.

CARL W. BRENN.
